SWITCH MACHINE FOR RAILROADS

Filed Aug. 26, 1929

FIG. 1.

FIG. 2.

FIG. 3.

INVENTOR

W. K. Howe,
BY Neil H. Weston,
his ATTORNEY

UNITED STATES PATENT OFFICE

WINTHROP K. HOWE, OF ROCHESTER, NEW YORK, ASSIGNOR TO GENERAL RAILWAY SIGNAL COMPANY, OF ROCHESTER, NEW YORK

SWITCH MACHINE FOR RAILROADS

Application filed August 26, 1929. Serial No. 388,436.

This invention relates in general to track switch operation, and has more particular reference to a dual control selector for optionally placing a track switch under either hand or motor control.

The present invention is a continuation in part of applicant's co-pending application Ser. No. 354,039 filed April 10, 1929, and entitled "Switch machines."

10 It is believed possible, with failure of power, for example, and in combination with faulty manual operation of the dual control selector, described in detail in the above referred to application, to bring about the undesirable condition in which the switch points can be left in mid-position. This is of course undesirable and while it never occurs in the normal operation of the selector, it is a remote possibility as just pointed out.

20 The present invention provides means for positively assuring against faulty manipulation by the operator making possible a condition wherein the switch points can be left in mid-position. This is accomplished by providing an interlock between the selector lever and the hand throw lever making it impossible to operate the selector lever unless the hand throw lever be in one or the other of its extreme positions and more important, making it impossible to operate the hand throw lever unless the selector lever is in the hand operating position, as distinguished from its motor operating position.

25 Further objects, purposes and characteristic features of this invention will appear as the description progresses, reference being made to the accompanying drawings showing, solely by way of example, and in no manner whatsoever in a limiting sense, one form 30 which the invention can assume.

In the drawings:-

Fig. 1 is a plan view of structure embodying the present invention, with parts shown in section.

45 Fig. 2 is a side elevation, with parts shown in section.

Fig. 3 is a detail sectional view, with parts shown in elevation, of the interlock between the selector and hand throw levers.

50 Referring now to the drawings, there is

shown in Figs. 1 and 2, in much the same manner as shown in the corresponding figures in the above referred to Howe application, hand operated and power operated means for throwing a track switch.

55 Mounted to rotate on a shaft 14, is a hand driven gear 11, connected up with a hand throw lever HT whereby swinging of the lever HT through an arc of approximately 210°, rotates gear 11 sufficiently to throw a track switch from normal to reverse, or vice versa, if gear 11 be connected up to drive shaft 14.

60 Likewise there is shown a gear 5, connected up to a motor, not shown, and arranged to drive a gear 6, which in turn drives a gear 7, which is furnished with a clutch member B, the clutch member B and the gear 7 being mounted to rotate on shaft 14. Here again, gear 7, when coupled up to drive shaft 14, can 65 throw a track switch from normal to reverse or vice versa.

65 Slidably, but non-rotatably mounted on shaft 14, is a shiftable clutch member C, arranged to couple up either the hand driven clutch member A, or the motor driven clutch member B, to drive the shaft 14. It should be noted that the shiftable clutch member C is so arranged as to uncouple with one of the clutch members A and B, only after it has 70 coupled with the other clutch member B or A.

75 The shiftable clutch member C is slidably shifted on shaft 14, by means of a fork member 27 and spring operators 36 and 37, by means of the selector lever S. On moving selector levers from its shown position, for example, to a position approximately 180° therefrom, the clutch member C is moved from its shown position, for motor operation of the switch points, to the position for hand operation of the switch points, in which it engages with clutch member A and disengages from clutch member B. The spring drive is arranged, as described in the above

80 referred to application to Howe, and as shown in the present drawings, to bias the shiftable clutch member C in the desired direction, whereby, if the member A or B, as the case may be, is not in proper position for immediate engagement with C, when it 85 90 95 100

has been rotated into proper position for engagement, the spring drive will immediately cause the desired engagement.

Shaft 14 carries a crank 22, furnished with a roller 21 for operating a usual throw rod TR, for moving a track switch, and for operating usual lock bolts for cooperation with a usual lock rod, not shown.

It is, of course, contemplated that with the selector lever S in its shown position, which allows for motor operation of the track switch, the hand throw lever HT be left undisturbed. If the hand throw lever be operated, however, it will merely rotate gear 11, and attached clutch member A, idly on shaft 14.

On throwing the selector lever S to its other extreme position, for permitting hand operation of the track switch, it is assumed that the motor be not operated, and in order to assure that it is not so operated, means for breaking the energizing circuit for the switch machine motor has been provided, as explained in the above referred to application.

While not at all likely, it is possible, with a particular manner of manipulation of the selector lever S and the hand throw lever HT, occurring simultaneously with power off of the motor, to accidentally leave the track switch with its points in mid-position, and, of course, unlocked.

As in the Howe application, 354,039, the power operation of the track switch unlocks, throws, and then again locks up the switch.

With hand operation, on the initial operation, the track switch is unlocked, then thrown, and on subsequent hand operations, due to lost motion arrangements, the track switch is only thrown. Thus, in hand operation, the hand operated clutch member A is moved through a smaller operative angle than is the motor operated clutch member B.

Therefore, normally after hand operating the track switch, as occasion often arises as, for instance, in dispatching systems to so operate the switch by hand even though energy is available for power operation, on then throwing lever S over for power operation, the slideable clutch member C is out of registry with the power operated clutch member B. If energy be available at that moment for the motor, that is, if the block be unoccupied, or if power does not fail for any other reason, the motor is energized, and after idly moving its clutch member C a short angular distance, this clutch member B picks up slideable clutch member C which has been spring biased toward it by the selector lever S, and completes the throwing of the switch and the locking up of the switch.

If energy fails on the motor, however, when the operator changes over from hand operation to power operation by moving the

selector lever S to power operating position, he is very likely, on getting no operation, to attempt to throw the switch by hand, by moving HT, without first moving selector lever S back to its hand operating position. This results in hand moving the slideable clutch member C, (and of course the track switch) to the position in which it can engage with the motor operated clutch member B, at which time it disengaged from A and engages with B, with the operator very likely completing the throw of hand throw lever HT and not realizing that he has lost operative connection with the track switch, and hence has not thrown it as he believes.

It is to be assumed, of course, that an operator, after throwing the selector lever S to the position for motor operation of the track switch, will not operate the hand throw lever. Should he so operate the hand throw lever, however, the above undesirable condition may be brought about.

To positively guard against the switch points being moved to mid-position and left there, the interlocking means, shown in detail in Fig. 3, is provided.

Between the hub 40 of lever S, and the hub 41 of lever HT, is a fixed plate member 42, slideably carrying a lock dog 43 of a length slightly greater than the thickness of plate 42. Provided in hub 40 is a notch 44 for at times receiving one end of lock dog 43, while in hub 41 are provided diagonally opposite notches 45 and 46 for likewise receiving, at times, one end of lock dog 43.

In the position of parts shown in Figs. 1-3, the selector lever S is placed for motor operation of the throw rod TR. As clearly seen from Fig. 3, lock dog 43 has been forced, by hub 40, into notch 45 of hub 41 of hand throw lever HT, whereby to lock the hand throw lever against any operation whatsoever. Thus, when selector lever S is in the position for motor operation of the track switch, an operator is powerless to manipulate the hand throw lever HT.

On throwing the selector lever S to its other extreme position, the hand operating position, notch 44 in hub 40 comes in line with lock dog 43, whereby hand throw lever HT can be operated to operate the track switch, lock dog 43 being forced into the notch 44 and out of notch 45 or 46, as the case may be.

In the above manner, an interlock between the hand throw lever HT, and the selector lever S, is provided, which prevents operation of the hand throw lever unless the selector lever is positioned for hand operation, and furthermore prevents moving of the selector lever unless the hand throw lever is in one or the other of its extreme positions.

The above rather specific description of a device embodying this invention, is given

solely by way of illustration, and is not intended, in any manner whatsoever, in a limiting sense. Obviously, this invention can assume many different physical forms, and is susceptible of various modifications, and all such forms and modifications are desired to be included by this invention, as come within the scope of the appended claims.

Having described my invention, I now claim:—

1. In combination, in a switch operator selector, a switch throw rod, a hand operable drive member, a power operable drive member, a clutch having a member movable to connect up the throw rod to either the hand or the power operable drive member, a selector for moving the movable clutch member, and means preventing operation of the hand operable drive member unless the selector is in its hand operable position.

2. In combination, in a dual selector for the operation of a track switch either by hand or by power, a selector movable to either of two positions for respectively permitting switch operation by hand or by power, a hand operated member for operating the track switch, and interlocking means between the hand operated member and the selector whereby to prevent operation of the hand operated member unless the selector is in the position corresponding to hand operation of the switch.

3. In combination, in a dual selector for the operation of a track switch either by hand or by power, a selector movable to either of two positions for respectively permitting switch operation by hand or by power, a hand operated member for operating the track switch, and interlocking means between the hand operated member and the selector whereby to prevent operation of the hand operated member unless the selector is in the position corresponding to hand operation of the switch, said interlocking means operating to prevent movement of the selector unless the hand operable member is in either one of its extreme positions corresponding to the completely thrown positions of the track switch.

4. In combination, in a dual selector for the operation of a track switch by hand or by power, a selector movable to either of two positions for respectively permitting switch operation by hand or by power, a hand operated member for operating the track switch, and interlocking means between the hand operated member and the selector whereby to prevent operation of the hand operated member unless the selector is in the position corresponding to hand operation of the switch, the interlocking means including a member movable with the hand operated member, a member movable with the selector, a fixed member carrying a projecting lock dog, and notches in the members connected to the se-

lector and the hand operated member for at times receiving said lock dog.

5. In combination, in a dual selector for the operation of a track switch either by hand or by power, a selector movable to either of two positions for respectively permitting switch operation by hand or by power, a hand operated member for operating the track switch, and interlocking means between the hand operated member and the selector whereby to prevent operation of the hand operated member unless the selector is in the position corresponding to hand operation of the switch, said interlocking means operating to prevent movement of the selector unless the hand operable member is in either one of its extreme positions corresponding to the completely thrown positions of the track switch, the interlocked means including a member movable with the hand operated member, a member movable with the selector, a fixed member carrying a projecting lock dog, and notches in the members connected to the selector and the hand operated member for at times receiving said lock dog.

6. In combination with a throw rod for operating a track switch, a hand operated member and a power driven member for optionally moving the throw rod, a selector movable to either of two extreme positions for connecting up the throw rod to be operated either by hand or by power, and means preventing operation of the hand operated member unless the selector be in its hand operating position.

7. In combination with a throw rod for operating a track switch, a hand operated member and a power driven member for optionally moving the throw rod, a selector movable to either of two extreme positions for connecting up the throw rod to be operated either by hand or by power, and interlocking means between the hand operated, and power driven, members.

8. In combination with a throw rod for operating a track switch, a hand operated member and a power driven member for optionally moving the throw rod, a selector movable to either of two extreme positions for connecting up the throw rod to be operated either by hand or by power, and means preventing operation of the hand operated member unless the selector be in its hand operating position, the hand operating member being movable to either of two extreme positions corresponding to the completely thrown positions of a track switch, said interlocking means preventing movement of the selector unless the hand operated member be in one of its extreme positions.

In testimony whereof I affix my signature.
WINTHROP K. HOWE.
